UNITED STATES PATENT OFFICE.

FREDERICK JOHN BONNALIE, OF CHESTER, ENGLAND.

MATRIX DEVICE.

1,165,149.

Specification of Letters Patent. Patented Dec. 21, 1915.

Application filed December 22, 1914. Serial No. 878,551.

To all whom it may concern:

Be it known that I, FREDERICK JOHN BONNALIE, a subject of the King of Great Britain, and resident of 7 Abbey Square, Chester, in the county of Chester, England, have invented new and useful Improvements in Matrix Devices, of which the following is a specification.

This invention relates to matrix devices for use in stopping or filling teeth or for similar purposes and comprises improvements in the invention forming the subject of my prior Patent No. 1,097,520, dated May 19th, 1914.

In the first construction of matrix device described in the specification of the aforesaid patent, the ends of the looped matrix band after being passed closely together through a slot in a frame or holder and in engagement with a roller, are secured by means of a set-screw within a slot in a block mounted upon a rod which is adapted to slide within a tubular portion of the holder for the purpose of adjusting the size of the loop of the matrix band. The said set-screw extends forwardly from the slot in the block and if it be desired to release the band from the holder when the device is in the mouth of a patient, as is found to be an advantage in practice, it is necessary to pass a suitable tool into the mouth in order to loosen the set-screw. The latter is also liable to come into contact with the rubber and clamp usually placed around the gum during a stopping or filling operation.

Now the present invention has for object to provide an improved construction of matrix device in which the set-screw is so arranged that it can be readily loosened from outside of the mouth of the patient and at the same time will not interfere with the aforesaid rubber and clamp.

According to this invention the rod to which the block is fixed, is made hollow for the reception of the set-screw which extends rearwardly of the matrix device beyond the rear end of the said hollow rod so that when the device is in use, the head of the screw is outside of the mouth and the screw can thus be easily turned by hand. It is also impossible by this arrangement for the set-screw to come into contact with the rubber or the clamp because it extends rearwardly and not forwardly from the slot in the block in which the ends of the matrix band are clamped. The set-screw may be threaded

for only a part or for the whole of its length, and the above-mentioned hollow rod may be correspondingly screw-threaded internally to allow of adjustment of the screw. 60

In order to enable the invention to be readily understood reference is directed to the accompanying drawings, wherein,

Figure 1 is a plan view of the improved matrix device, on an enlarged scale. Fig. 2 65 is an elevation thereof omitting the matrix band, and, Fig. 3 is a sectional plan view.

In the construction of matrix device illustrated in the drawing, the frame or holder carrying the matrix band *a* consists as in the 70 previous invention of an L-shaped member *b* one arm of which is provided with a transverse slot *l* having a roller *o* mounted therein for facilitating the movement of the band *a* through the slot and the other arm of 75 which carries a tubular stem *c* within which a rod *d* is adapted to move axially. In the present invention, however, this rod *d* is made hollow for the reception of the rearwardly extending set-screw *n*, and also the 80 block *e* is provided with an axial hole *e'* which forms a continuation of the bore of the hollow rod *d* as will be clearly seen from Fig. 3, and extends as far as the slot *m* in the block *e*, wherein the ends of the matrix 85 band *a* are adapted to be clamped; so that the forward end of the set-screw *n* may enter the slot and clamp the ends of the band. The set-screw *n* is suitably screw-threaded for part of its length at or near its 90 forward end, as indicated at *n'* in Fig. 3, for engaging with a female-threaded portion on the interior of the hollow rod *d* or in the hole *e'* or both within the hollow rod *d* and the hole *e'*. The rear end of the set-screw *n* projects beyond the rear end of the hollow rod *d* and is provided with a milled 95 head as shown so that it can be turned when desired.

It will now be readily understood that the 100 set-screw *n* can be easily turned by hand from outside the patient's mouth when the matrix device is in use, consequently without necessitating the use of a tool for the purpose, and therefore the matrix band *a* 105 can be readily released from the holder when the device is in the mouth of a patient thereby also avoiding any possibility of injuring the stopping or filling.

The hollow rod *d* is screw-threaded externally at or toward its rear end as at *h* for the reception of a nut *k* for moving the rod 110

longitudinally, the nut bearing against the end of the tubular stem *c*. In order, however, to obviate the necessity of moving the hollow rod *d* by hand upon loosening the nut 5 *h* as is the case with the device illustrated in my prior patent the tubular stem *c* may be provided with a bracket 1 at its rear end which bracket has an inwardly projecting part 2 taking into an annular groove 3 in a 10 boss 4 on the nut, see especially Fig. 2. The nut is thus prevented from moving axially but whichever way it be turned it will cause movement of the hollow rod *d*.

Moreover, in order to indicate when the 15 slot *m* in the block *e* and the slot *l* in the L-shaped part *b* of the holder are disposed opposite each other so as to enable the ends of the band *a* to be readily passed through the slots prior to the clamping with the set 20 screw *n*, the block and the slotted arm of the member *b* may be provided with indicating marks, as shown for instance at 5 in Fig. 1, these marks being in alinement when the two slots aforesaid are opposite each other.

25 I claim:

1. A matrix device for use in filling teeth and for similar purposes, comprising a flexible matrix band bent into the form of a loop, a frame having a slot through which 30 both ends of said band are passed closely together, a hollow rod axially movable upon said frame, a clamp member at the forward end of said hollow rod, a set-screw adapted to impinge on said band for clamping the 35 ends of the latter to said clamp member, said set-screw extending rearwardly from the clamp member through said hollow rod and having its head beyond the rear end of the rod, and adjusting mechanism for effect- 40 ing axial movement of said rod.

2. A matrix device for use in filling teeth and for similar purposes, comprising a flexible matrix band bent into the form of a loop, a tubular frame having a slot at one 45 end through which both ends of said band are passed closely together, a roller mounted in said slot and engaged by said band, a hollow rod axially movable upon said frame, a clamp member at the forward end of said 50 hollow rod, a set-screw adapted to impinge on said band for clamping the ends of the

latter to said clamp member, said set-screw extending rearwardly from the clamp member through said hollow rod and having its head beyond the rear end of the rod, and 55 adjusting mechanism for effecting axial movement of said rod.

3. A matrix device for use in filling teeth and for similar purposes, comprising a flexible matrix band bent into the form of a loop, a tubular frame having a slot through which both ends of said band are passed closely together a roller mounted in said slot and engaged by said band, a hollow rod axially movable upon said frame, a block 65 on the forward end of said hollow rod provided with a slot for receiving the ends of said band, and with a screw-threaded hole extending from the slot to the rear of the block, a set-screw for clamping said ends 70 in said slot, said set-screw engaging at its front end in said screw-threaded hole and extending rearwardly through the bore of said hollow rod so that its head is beyond the rear end of the rod, and adjusting mech- 75 anism for effecting axial movement of said hollow rod.

4. A matrix device for use in filling teeth and for similar purposes, comprising a flexible matrix band bent into the form of a loop, a member having a slot through which both ends of said band are passed closely together, a roller mounted in said slot and engaged by said band, a tubular stem attached to said slotted member a hollow rod 85 in said tubular stem, a clamp member at the forward end of said hollow rod, a set-screw for clamping the ends of said band to said clamp member, said set-screw extending rearwardly from the clamp member through 90 said hollow rod and having its head beyond the rear end of the rod, a nut threaded on the rear end of the rod, a grooved boss on said nut, and a bracket at the rear end of said tubular stem provided with a projecting 95 part for engaging the grooved boss of the nut, substantially as and for the purpose set forth.

FREDERICK JOHN BONNALIE.
